PORTABLE POWER ACTUATED CLIP-APPLYING TOOL

Harrison C. Lingle, Wilmette, and Arthur Langas,
Glenview, Ill., assignors to Hartco Company, Wilmette,
Ill.

Filed Sept. 4, 1969, Ser. No. 19,010

Term of patent 14 years

Int. Cl. D8—02

U.S. Cl. D8—49

FIG. 1

FIG. 2

FIG. 1 is a right front perspective view of a portable power-actuated clip-applying tool embodying our ornamental design;

FIG. 2 is a side elevational view of the tool;

FIG. 3 is a front elevational view of the tool; and

FIG. 4 is a left front perspective view of the tool.

We claim:

The ornamental design for a portable power-actuated clip-applying tool, substantially as shown and described.
